BREADBOX

Louis H. Barnett and Harris Brin, Fort Worth, Tex., assignors to Loma Plastics, Inc., Fort Worth, Tex., a corporation of Texas

Application August 10, 1951, Serial No. 241,230

3 Claims. (Cl. 220—4)

1

This invention relates to bread boxes and the like.

An object of the invention is to provide a box of the described class which may be quickly and conveniently assembled during its construction.

Another object of the invention is to provide a unique hinge construction for carrying out the foregoing object.

Although the preferred form of the invention is made of molded plastic, it is to be understood that the invention is not limited thereto. The bread box shown may be made of sheet metal or any other suitable material capable of being shaped to form the parts and arrangement hereinafter described.

These and other objects of the invention will become apparent from the following description and the accompanying drawing, wherein:

Figure 1 is a perspective view of a bread box or the like embodying the features of the present invention.

Figure 2 is an enlarged broken perspective view of the hinge construction.

Figure 3 is a vertical transverse sectional view of the hinge illustrated in Figure 2, and

Figure 4 is an exploded transverse sectional view showing a preferred means of assembly.

The form of the invention shown includes a rectangular base 10 having integral projecting feet 11 on the bottom and near the corners thereof. The bread box case 12 is substantially rectangular, and includes an outwardly directed shouldered flange 13 around its lower periphery for receiving the base 10. The back 14, ends 15, and top 16 of the core 12 are substantially rectangular, except that the forward upper corners of said ends are arcuate, as indicated by the numeral 17. Small vent holes 18 are provided through the top 16.

The forward side 19 of the case 12 is provided with an opening 20, the upper and lower edges 21 and 22 of which are parallel with each other and are located near opposite ends of the referred to arcs 17. The vertical edges 23 and 24 of the opening 20 are positioned inwardly of the case ends 15, as shown in Figure 1. There is an arcuate cover 25 adapted to fit inwardly of the opening 20 and close the latter, and which cover is hingedly supported for rotation about an axis located along the axial center defined by the arcuate corners of the case ends 15. The hinge support referred to is comprised of brackets 26 supported on the base 10 near each end thereof, and which brackets are comprised of vertical supporting members 27 having out-

2

wardly directed perpendicular flanges 28 on each side thereof. Beneath the upper ends of the brackets 26 there are arcuate flanges or bearings 29 adapted to receive disk-like journals 30 which are integral with the apex ends of a triangular arm 31 integral with and perpendicular to the arcuate cover 25. It is to be understood that the cover 25 is provided with an arm 31 on each end thereof, and that the respective journals 30 fit between the inner surfaces of the end walls 15 and the upwardly projecting ends 32 of the brackets 26.

Other details of construction include an elongated stop 33 projecting from the outer surface 15 of the cover 25 and near the lower edge thereof and arranged to engage the lower opening edge 22. A handle 34 may be provided on the cover 25 above the stop 33, and which handle also serves as the stop when the cover is in its raised position and in contact with the upper edge 21 of the case opening 20. Projections 35 extend upwardly from the base 10 near the back edge thereof so as to prevent bread or other articles within the case 12 from interfering with the operation of the cover 25.

As shown in Figure 4, the bread box is assembled by inverting the case 12, and placing the cover 25 therein with the disk-like journals 30 in an upward position. The base 10 is inverted and the arcuate bearings 29 are caused to engage the journals 30, and the base is then cemented or otherwise bonded in place. It is pointed out that the opening 20 may be used for moving the disk-like journals 30 to the proper position to be received within the arcuate bearings 29 during the assembly operation.

The described form of the invention is not limited to the specific construction herein shown and described, but may be made in many ways within the scope of the appended claims.

What is claimed is:

1. A plastic bread box or the like comprising a rectangular case having a substantially flat bottom secured to the bottom of said case, said case including arcuate upper forward corners, an opening in said case between said upper forward corners and having the upper and lower edges thereof parallel with each other, and with the lower edges spaced from the bottom of said case, upwardly directed plastic bearings having relatively large arcuate bearing surfaces, said bearings being supported by said bottom on each side thereof interiorly of said case and equally spaced from the front edge of said base, the radial centers of said bearings being spaced at a vertical

distance from said bottom substantially the same distance as said lower edge of said opening is spaced from said base, relatively large disk-like journals received within said bearing surfaces, retaining flanges integral with the inner peripheries of said arcuate bearings and extending toward the axis thereof and engaging the opposing flat peripheries of said disk-like journals, an arcuate plastic cover positioned within said opening, and substantially triangular arms integrally connected with the ends of said cover and with said journals.

2. A plastic bread box or the like comprising a rectangular case having a substantially flat bottom, the sides of the case including arcuate upper forward corners, an access opening in said case between said upper forward corners and having the upper and lower edges thereof parallel with each other, and with the lower edge spaced from the bottom of said case, support means extending upwardly from said bottom integral therewith on each side thereof, an arcuate plastic cover positioned within said opening, and an arm integrally connected with each side of said cover and extending inwardly along its adjacent side of the case and terminating integral means cooperating with integral means on the upper portion of said support means for pivotally connecting the cover to the case, one of said integral means forming said pivotal connection comprising relatively large arcuate bearing surfaces and the other of said integral means comprising relatively large journals received within the bearing surfaces and retained therein against inward axial movement by flanges carried by one of said integral means, said pivotal connection being spaced at a vertical distance from said bottom substantially the same distance as said lower edge of said opening is spaced from said bottom.

3. A plastic bread box or the like comprising a rectangular case having a substantially flat bottom, the sides of the case including arcuate upper forward corners, an access opening in said case between said upper forward corners and having the upper and lower edges thereof parallel with each other, and with the lower edge

spaced from the bottom of said case, support means extending upwardly from said bottom integral therewith on each side thereof, an arcuate plastic cover positioned within said opening, and an arm integrally connected with each side of said cover and extending inwardly along its adjacent side of the case and terminating in integral means cooperating with integral means carried by the upper portion of said support means for pivotally connecting the cover to the case, one of said integral means forming said pivotal connection comprising relatively large arcuate bearing surfaces and the other of said integral means comprising relatively large journals received within the bearing surfaces, said journals and bearing surfaces being retained against relative axial displacement by flanges carried by one of said integral means, said pivotal connection being spaced at a vertical distance from said bottom substantially the same distance as said lower edge of said opening is spaced from said bottom.
